CALF WEANER

Filed April 22, 1931

Inventor
Charles C. Quinn
by Quinn & League Atty.

UNITED STATES PATENT OFFICE

CHARLES C. QUINN, OF BOONE, IOWA, ASSIGNOR TO QUINN WIRE & IRON WORKS, OF BOONE, IOWA, A CORPORATION OF IOWA

CALF WEAVER

Application filed April 22, 1931. Serial No. 531,983.

The object of my invention is to provide a calf weaner of simple, durable and inexpensive construction, having improved means for fastening the same to the animal's head.

More specifically it is the object of my invention to provide in a calf weaner of that type comprising a semi-cylindrical body portion, having at one end a series of radially projecting teeth, a single flexible member for securing the same to the animal's head, and in connection therewith improved fastening means whereby the flexible member is adjustably mounted to the weaner to increase or decrease the size of the throat strap, and a single fastening member for increasing or decreasing the size of the head strap, the fastening being so arranged that the head strap may be supported in one plane and the throat strap in another plane angular therewith.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a side elevation of my improved weaner.

Figure 2 is an end elevation of same.

Figure 3 is a detail sectional view taken on the line 3—3 of Figure 1.

My improved weaner comprises a body portion 10, which is formed preferably of light sheet metal and substantially of semi-cylindrical formation, said body having a circumferential rib 11 near its central portion, and a series of openings 12, which serve to lighten the body, and at the same time permit ventilation.

One front edge of the body is provided with a series of forwardly and radially projecting points 13. The back and bottom edges of the body are provided with an outwardly extending flange portion 14 to stiffen the body, and to provide slightly rounded back and bottom edges.

Formed in the back end of each lower edge of the body is a pair of slots 15 and 16. The slot 15 is substantially parallel with the bot-

tom edge of the body, while the slot 16 is substantially at 45° to the said bottom edge. The slots 15 and 16 are designed to receive a webbing 17 threaded through both sets of slots 15 and 16 to form a throat portion 18. The free ends are fastened together by means of a buckle 19 or similar fastening device to form the head portion 20.

The webbing is threaded through the slot 16 from the outside, thence adjacent to the inner surface of the body 10, then outwardly through the slots 15. By this arrangement the webbing is locked against longitudinal movement through the slots, when the webbing is adjacent to the inner face.

If it is desired to increase or decrease the size of the throat portion 18, then the webbing 20 may be pushed inwardly, causing the inner portion to be looped, after which the portion 18 may be pulled outwardly, thereby increasing the size of the throat portion. A reverse operation would decrease the size of the throat portion. The buckle 19 provides means for adjusting the size of the head portion.

Thus it will be seen that I have provided an improved fastening device for the body portion, which is formed preferably of webbing, which is comparatively soft, and at the same time I have provided a fastener formed of a single strip of webbing in which either or both of the throat and head members may be adjusted at the will of the operator to fit animals of various sizes.

Furthermore, by providing the reinforcing rib 11 and the flange 14, means is provided whereby the body 10 may be formed of comparatively light material, and at the same time have sufficient strength for supporting the pointed ends 13.

I claim as my invention:

1. A calf weaner comprising a body portion formed of sheet metal and of substantially semi-cylindrical formation, one end of said body being provided with forwardly and radially projecting teeth, and its back and lower edges provided with an outwardly projecting flange, the lower ends of said body each having a pair of webbing receiving

slots, one of said slots being inclined relative to the other, a single webbing threaded through said slots to form throat and head portions, and a buckle for securing the free ends of said webbing.

2. A calf weaner comprising a semi-cylindrical body formed of sheet material, each lower edge of said body having a pair of slots, one inclined relative to the other, a single piece of flexible material threaded through both sets of slots to form a looped throat portion and a looped head portion, and means for detachably and adjustably connecting the free ends of said flexible member.

3. A calf weaner comprising a body portion formed of sheet metal and of substantially semi-cylindrical formation, one end of said body being provided with forwardly and radially projecting teeth, its back and lower edges being provided with an outwardly projecting flange, the central portion of said body having a circumferential bead for reinforcing the body, and openings for ventilating purposes, the lower end of said body having a pair of webbing receiving slots, one of said slots being inclined relative to the other, a single webbing threaded through said slots to form throat and head portions, and a buckle for securing the free ends of said webbing.

Des Moines, Iowa, April 16, 1931.
CHARLES C. QUINN.
